UNITED STATES PATENT OFFICE.

FRANK M. GARLAND, OF NEW HAVEN, CONNECTICUT.

PACKAGE OF AMMUNITION.

SPECIFICATION forming part of Letters Patent No. 513,567, dated January 30, 1894.

Application filed April 3, 1893. Serial No. 468,922. (No model.)

To all whom it may concern:

Be it known that I, FRANK M. GARLAND, a citizen of the United States, residing at New Haven, in the county of New Haven and State of Connecticut, have invented certain new and useful Improvements in Packages of Ammunition, of which the following is a full, clear, and exact specification.

The invention relates to the class of ammunition provided for rapid-fire machine guns; and the object is to provide such a package of ammunition that by means of it a large number of cartridges can be continuously fed into the gun and fired with great rapidity 15 without leading or otherwise fouling or damaging the barrels or impairing their efficiency.

Referring to the accompanying drawings, Figure 1 is an edge view of such a package. Fig. 2 is an edge view of the package unrolled. Fig. 3 is a plan view of the same. Fig. 4 is a detail enlarged plan of a small portion of such a package; and Fig. 5 is an enlarged section of one of the bullets used in the package.

25 In the views 1 indicates the body of the package which is formed of a flexible belt or strap of leather, webbing or other similar material having a suitable texture. To one surface of this belt are secured by prongs or rivets a number of clips 2 having spring arms for clasping and holding with a yielding grasp the cartridges 3 and 4. These cartridges have shells formed in any common shape of brass or other suitable material, and are provided 35 with bullet 3' and 4'. The bullets 3' of the cartridges 3, are formed in the approved shape to the correct size to fit the rifling of the barrels, so that when fired they take the proper motion to have the best possible flight and 40 penetration; while the bullets 4' of the cartridges 4, are somewhat smaller in diameter than the cartridges 3', and are provided with rings or bands 5 of brass, copper, or other similar metal, of different density from the bodies of the bullets. These bands are set into grooves in the bodies of the bullets, and are formed so that their exterior diameters are larger than the exterior diameters of the smaller bullets, and fit the rifling of the barrels 45 so as to scrape them out when they are

fired. It is preferred to secure a swab or cleaner 6, of leather, cloth or other soft material to these bullets, by catching one edge under these rings, so that after the rings on the bullets have cleared the rifling of the barrel 55 of any fouling substance, the swab will follow and wipe and polish the barrel. These swabs may be lubricated with oil, or soaked with any other substance whereby they will grease the barrels when fired. The larger number of the 60 cartridges of the package are provided with the bullets of the customary size and shape, while at intervals between these are placed the cleaning bullets, so that during firing the barrels are periodically cleared of anything 65 which would impair the accuracy or the efficiency of the firing. If the package is to be used with a gun having a single barrel, it is preferred to have one of these cleaning cartridges placed between every one, two, or 70 three hundred of the other cartridges of the package; while if they are to be used in a two-barrel gun two of these cartridges can be placed at such intervals; and if used with a ten-barrel gun, ten of them can be placed together after the desired number of regular cartridges.

This package is simple, cheap and efficient, and when it is used with a gun, although subjected to very rapid fire the barrels are periodically cleaned by these cleaning bullets, so that a continuous fire can be kept up without danger of leading or fouling the barrels, which, besides increasing the accuracy and efficiency, tends to lessen the heating of the 85 barrels.

I claim as my invention—

1. A package of ammunition, consisting of a body holding a number of cartridges, said cartridges having bullets of different diameters, the bullets of smaller diameter being provided with rings of metal of different density, the exterior diameters of said rings being larger than the exterior diameters of the smaller bullets, substantially as specified. 95

2. A package of ammunition, consisting of a body holding a number of cartridges, said cartridges having bullets of different diameters, the bullets of smaller diameter being provided with rings of metal of different den-

sity and cleaning swabs, the exterior diameters of the said rings being larger than the exterior diameters of the smaller bullets, substantially as specified.

5. 3. A package of ammunition, consisting of a flexible body holding a number of cartridges, said cartridges having bullets of different diameters, the bullets of smaller diameter being provided with rings of metal of

different density and cleaning swabs held by the rings, the exterior diameters of said rings being the same as the exterior diameters of the larger bullets, substantially as specified.

FRANK M. GARLAND.
